UNITED STATES PATENT OFFICE.

JAMES A. BROGAN, OF LAWRENCE, MASSACHUSETTS, ASSIGNOR TO UNITED SHOE MACHINERY CORPORATION, OF PATERSON, NEW JERSEY, A CORPORATION OF NEW JERSEY.

FASTENING-INSERTING MACHINE.

1,360,090.

Specification of Letters Patent. Patented Nov. 23, 1920.

Application filed February 6, 1919. Serial No. 275,400.

To all whom it may concern:

Be it known that I, JAMES A. BROGAN, a citizen of the United States, and resident of Lawrence, in the county of Essex and State 5 of Massachusetts, have invented certain Improvements in Fastening-Inserting Machines, of which the following description, in connection with the accompanying drawings, is a specification, like reference characters on the drawings indicating like parts in the several figures.

This invention pertains to fastening inserting machines and will be disclosed, by way of example, as embodied in a machine 15 for inserting wire fastenings of the type shown in United States Patent No. 490,621, granted to Louis Goddu, January 24, 1893.

The machine is provided with a wire carrying spindle slotted to receive grippers 20 which engage the wire to feed it into the work, and this spindle was originally formed with a solid end provided with a central opening for the wire. Difficulty was experienced in the operation of machines as 25 thus constructed arising from the frequent failure of the grippers to force the wire through the solid end of the spindle by reason of an enlargement or other imperfection in the wire or in consequence of the wire being upset or wedged into a slot of the spindle 30 resulting, for example, from its engagement with some unusual obstruction such as a nail or tack in a shoe. Inasmuch as the grippers are positively driven, failure of the wire to 35 pass through the passage of the throat caused breakage of the grippers or of some other part connected therewith. Moreover, it was necessary to remove the solid end from the spindle and to draw out the imperfect 40 or upset portion of the wire before the operation of the machine could be resumed.

In order to obviate these difficulties, it was proposed in United States Patent No. 565,073, granted Aug. 4, 1896, to Louis 45 Goddu to form a spindle with slots extending unobstructedly to its delivery end. The walls of the spindle between the slots are of considerable rigidity so as to retain their positions under normal conditions of the insertion of the wire and thus effectively to guide 50 and support the wire but may be flexed outwardly when required by abnormal formations of the wire to permit passage of the wire from the spindle. Although such modification of the spindle did, in fact, relieve

many of the difficulties which it was designed to obviate, nevertheless, the spindle, as so modified, is sometimes defective in its operation, particularly under certain conditions, such, for example, as when operating 60 on thick, heavy stock requiring the insertion of a long section of wire into the work. A relatively small increase in the length of the fastening inserted increases greatly the force required to thrust the fastening into the 65 work. Moreover, the longer the fastening inserted, the farther from the end of the spindle the wire is engaged by the grippers, thus enhancing its tendency to force the walls of the spindle outwardly and to buckle 70 or be upset in one of the slots of the spindle. For the above and other reasons, it often happens that the walls of the spindle between the slots become permanently sprung outwardly thus increasing the size of the 75 bore of the spindle so that the wire is not properly guided and supported in its movement into the work and also permitting the wire to be forced laterally into the enlarged 80 slots of the spindle.

One of the objects of the invention is so to construct a fastening guide having a bore of substantially uniform diameter, for instance, the wire carrying spindle of a machine for inserting wire fastenings, that it will be efficient and reliable in operation under all conditions and even after long continued use of the machine. To this end, an important feature of the invention resides in the provision of means tending to contract the guide. In 90 the illustrated construction, such means is of a character to insure the return of the walls of the guide to normal position whenever they are sprung therefrom.

Although the invention will hereinafter 95 be described in its application to a machine for inserting screw-threaded fastenings, it is recognized that the use of the invention is not restricted thereto but that the invention may be utilized in other relations including embodiment in fastening inserting machines of other types. Accordingly, it is intended that the scope of the invention shall be limited only as required by the 100 claims.

In the drawings;

Figure 1 is a cross-sectional view in elevation of the wire-carrying spindle and associated parts of a machine for inserting screw-threaded fastenings;

105

110

Fig. 2 is a view of the spindle extension on an enlarged scale, and

Fig. 3 is a plan view in cross-section taken along the line 3—3 of Fig. 2 and looking 5 in the direction of the arrow.

The machine comprises a wire-carrying spindle 2 in which is threaded the spindle extension 4 having a bore of substantially uniform diameter in alignment with the 10 bore of the spindle. The spindle extension is formed with slots 6 extending radially outwardly from said bore and designed to receive grippers 8 reciprocable lengthwise of the spindle to force the wire into the 15 work. The grippers 8 are carried by a holder 10 sleeved on the spindle 2 and having slots to receive blocks 12 and friction members 14 interposed between said blocks and the periphery of the spindle 2. An internally tapered and threaded ring 16 meshes 20 with teeth on the blocks 12 and may be turned to press the blocks 12 and friction members 14 against the spindle 2 thereby to retain the sleeve 10 normally in fixed position 25 on the spindle.

The grippers 8 are operated by a sleeve 18 slidably mounted on the spindle 2 and inclosing the gripper holder 10 and being provided with rolls 19 for engagement with 30 inclined surfaces on the grippers 8. Slots 20 are formed in the sleeve 18 of greater length than the blocks 12, the construction being such that when the sleeve 18 is raised the lower walls of the slots 20 engage the 35 blocks 12 and raise the gripper holder 10 and grippers 8, whereas upon the downward movement of the sleeve 18, the rolls 19 engage the grippers 8 and close them upon the wire prior to the engagement of the upper 40 walls of the slots 20 with the blocks 12 to move the grippers downwardly to free the wire. The sleeve 18 derives its movement from a yoke 22 formed with a bearing on 45 which rides an annulus 24 threaded on the upper end of the sleeve. An annulus 26 on the sleeve underlies the yoke 22. The elements hereinbefore described are fully set forth in the patent to Louis Goddu, 490,621 in their relation to each other and to the 50 machine as a whole, for which reason a more complete exposition thereof is deemed unnecessary.

The walls of the spindle 4 intermediate between the slots 6 are, as hereinabove indicated, of considerable rigidity. Consequently, they remain fixed and unyielding during normal conditions of operation of the machine. The bore of the spindle is made of substantially uniform diameter, approximately equal to the diameter of the wire which it is desired to insert. Accordingly, the inner surfaces of the walls of the spindle contact with the wire at substantially all parts of its periphery except where

the walls are interrupted by the slots 6 and thus efficaciously support and guide the wire during its insertion into the work.

The force required to insert the wire into the work is very considerable, in consequence of which it is requisite that the grippers have 70 a firm hold on the wire. To this end, they are made as wide as practicable. Manifestly, however, the width of the grippers is limited by that of the slots which in turn must be less than the diameter of the wire 75 to preclude the forcing out of the wire through the slots. It will be understood from the foregoing, however, that the walls of the spindle may be flexed outwardly under certain conditions, as, for instance, 80 to permit the passage of an enlargement of the wire or of an upset portion of the wire, and it is apparent that, inasmuch as the walls are not perfectly elastic, repeated outward flexure will cause them to be permanently sprung or distended. Palpably, the walls of the spindle will not in such condition effectively support and guide the wire during its insertion, thus rendering the operation of the machine unreliable: 90 Moreover, the outward spreading of the walls enlarges the slots and thus greatly augments the likelihood of the buckling of the wire therein.

In accordance with this invention, means 95 is provided tending to return the walls of the spindle to normal position when moved therefrom, and, in the illustrated construction, such means comprises a spring 28 coiled in a groove formed in the tapered end of 100 the spindle extension 4. The force exerted inwardly by the spring 28 counteracts the tendency of the walls when distended not to return fully to their original positions and thus maintains the diameter of the bore 105 of the spindle uniform and prevents enlargement of the slots 6 by use of the machine. The spring 28 also adds to the resistance to outward flexure of the walls of the spindle thus preventing them from moving too 110 readily, yet permitting their movement when required by the character of the wire being operated upon.

Having described my invention, what I claim as new and desire to secure by Letters 115 Patent of the United States is:

1. In a machine for inserting fastenings, a fastening guide formed with a bore of substantially uniform diameter and slotted at its delivery end to permit expansion of 120 the guide when required by the character of the fastening passed therethrough, and means tending to contract the guide.

2. In a machine for inserting fastenings, a fastening guide slotted at its delivery end and having its walls intermediate between the slots normally rigid but constructed to yield when required to permit the passage

of a fastening therethrough, and means tending to return the walls to normal position when moved therefrom.

3. In a machine for inserting fastenings, 5 a fastening guide slotted at its delivery end and having its walls intermediate between the slots normally rigid but constructed to yield when required to permit the passage of a fastening therethrough, and a spring 10 for returning the walls to normal position when moved therefrom.

4. In a machine for inserting wire fastenings, a wire carrying spindle having slots therein continued unobstructedly to its delivery end and having its walls between said slots normally rigid but constructed to yield when required to permit the passage of the wire therethrough, and a spring coiled about 15 said walls tending to move said walls inwardly.

5. In a machine for inserting wire fasten-

ings, a wire carrying spindle having slots therein continued unobstructedly to its delivery end, wire feeding means movable in said slots to a point adjacent to the ends of 25 the slots, and means intermediate between the path of movement of the feeding means and the end of the spindle tending to move the walls of the spindle inwardly.

6. In a machine for inserting wire fastenings, a wire carrying spindle provided with slots continued unobstructedly to its delivery end and having a reduced lower end formed with an external annular groove, 30 wire feeding means movable in said slots, 35 and a spring coiled in said annular groove and tending to move the walls of said spindle inwardly.

In testimony whereof I have signed my name to this specification.

JAMES A. BROGAN.
